UNITED STATES PATENT OFFICE

2,428,905

BOILER

John Bilan, Flint, Mich.

Application June 12, 1944, Serial No. 539,818.

3 Claims. (Cl. 122—40)

1

The present invention relates to boilers, and has for its principal object the provision of an improved boiler for generating steam for heating radiators.

A still further object of the present invention is the provision of means for preheating the water in a boiler with means for converting the preheated water into steam.

A still further object of the present invention is the provision of a reservoir for supplying a constant flow of water into the boiler under pressure.

A still further object of the present invention is the provision of an auxiliary water supplying means into the boiler for converting the same into steam before the means of feeding water in the boiler from the reservoir and conversion thereof into steam become operative.

With the above general objects in view and others that will appear as the invention is better understood, the same consists in the novel construction, combination and arrangement of parts hereinafter more fully described and illustrated in the accompanying drawings and pointed out in the appended claims.

In the drawings forming a part of this application, and in which like designating characters refer to corresponding parts throughout the several views:

Fig. 1 is a transverse cross-sectional view through the boiler;

Fig. 2 is an elevational diagrammatic view, on a reduced scale, of the boiler, a radiator and a water reservoir, together with an auxiliary means for supplying water into the boiler before pressure has been generated in the reservoir for passing water therefrom into the boiler;

Fig. 3 is a cross-sectional view on a horizontal plane, on an enlarged scale, on line 3—3 of Fig. 1; and

Fig. 4 is an enlarged cross-sectional view through the seal and locking means between the boiler proper and its closure.

Referring in detail to the present drawings there is shown therein a fire box 10 having its side walls downwardly tapering, and having an integrally formed and inwardly projecting ledge 11 for the purpose of supporting grate 12. Grate 12 is adapted to receive a supply of fuel upon which the same is adapted to burn, while the fire box below grate 12 constitutes an ash compartment. Access into the fire generating compartment and ash compartment of fire box 10 is provided through doors (not shown) made in the end wall of said fire box 10.

2

Integrally formed with the upper end of side walls of fire box and inwardly projecting therefrom is flange 13 upon which the boiler rests as will be later apparent.

5 Boiler 14 includes a pair of troughs 15 in a longitudinal relation with the boiler, and each of said troughs has a side wall 16 and an inner wall 17. The latter two are continuous on transverse cross-section through the boiler, and form an upwardly extending inverted U-shaped bulge 18.

The lower portions of outer walls 16 of said troughs 15 are downwardly tapering and spaced from the adjacent tapering side walls of fire box 10 while the upper portions thereof are vertically disposed, as is clearly seen in Fig. 1.

10 Affixed to said upper vertical portion of the side walls 16 are angle irons 19 which, in the operative relation of the boiler with fire box, rest upon said flange 13, thereby supporting the boiler in an elevated position above grate 12.

15 Cooperating with said boiler 14 is a top closure 20, including roof 21 and integrally formed side wall 22.

20 Vertical wall 22 of said closure 20 is removed 25 from the vertical portions of walls 16, so that in the operative association of closure 20 with boiler 14 said wall 22 extends laterally and in a spaced relation with the side walls of said boiler 14, as is clearly seen in Fig. 1. Exteriorly of side wall of boiler 14 and downwardly depending from the upper edge thereof is an integrally formed continuous gutter 23, which receives quantity of cement or other suitable sealing material 24 within which the lower edge of side wall 22 of closure 20 is embedded, thereby forming an impervious seal therebetween and said boiler 14.

25 Below said gutter 23 the side wall of boiler 14 has a continuous angle iron 25 affixed thereto and side wall 22 of closure 20 has a similar angle iron 26, the latter disposed above the edge of

30 said wall 22. A plurality of bolts 27 are extended through the horizontal portions of said angle irons 25 and 26 in a spaced relation, the upper ends of said bolts receiving in a threaded engagement nuts 27'. Said angle irons 25 and 26 and bolts 27 constitute a clamping means between boiler 14 and closure 20 and maintain the edge of side wall 22 firmly embedded in cement 24, and thereby impervious seal is established and maintained between said boiler 14 and closure 20, preventing escape of steam between said boiler 14 and closure 20.

35 Through pipes 28 each trough 15 is adapted to receive a supply of water 29 thereto, said pipes 28 connecting through the end wall 30 of boiler

14. Set within each trough 15 at a predetermined level of water is sealing plate 31. Set in each sealing plate 31 is a pair of upright pipes 32 having their lower ends open and extended through said sealing plates 31 and set adjacent the bottoms of said troughs 15. The upper ends of each pair of said pipes 32 connect with horizontal pipe 33, each of which is disposed above each trough 15 and in a longitudinal relation therewith and above the plane running through the upper termination of bulge 18. These two horizontal pipes 33 have a lead pipe 34 connected thereto and centrally thereof which in turn by their opposite ends connect to a joint 35 to which in turn a horizontal perforated pipe 36 connects. Said pipe 36 is disposed above said bulge 18 and in a longitudinal relation therewith.

Water within troughs 15 will rise in pipes 32, and therefrom will pass into pipes 33 and 34 and into the perforated pipe 36 by means which will be later apparent. From the latter pipe water will spill through perforations in said pipe 36 upon the roof of bulge 18. By virtue of extreme heat generated below said bulge 18 any spilled water thereon will convert itself into steam. Any unconverted water will be partially retained by wings 37 provided laterally of bulge 18 and co-extensively thereof until eventually the water retained by said wings 37 will either pass through perforations 60, evaporate or any excess will spill itself over said wings and upon seal plates 31 from which it will eventually evaporate.

Referring to Fig. 2 there is shown a sealed reservoir 38 which is adapted to receive quantity of water from city water pipe. Connected with the lower end of said reservoir 38 is pipe 39 with which said pipes 28 connect, thereby supplying constantly water into troughs 15.

Connecting with the interior of the boiler and through closure 20 thereof is steam pipe 40 leading into the radiator 41 in a dwelling. Steam in said radiator 41 condenses, and the condensed water is led by return pipe 42, the latter connecting with said pipe 39 to again circulate with water passing through said pipe from reservoir 38 and into troughs 15. If any steam should pass through return pipe 42 into pipe 39 the same will be condensed in pipe 39.

Connected with boiler 14 and above the level of sealing plates 31 is pipe 43 which connects with the upper end of reservoir 38, permitting steam to pass into said reservoir 38 and into the upper end thereof so as to generate an amount of pressure within said reservoir 38. A pump P, schematically shown is connected in pipe 39 to force water under pressure into troughs 15 through pipes 28. Return pipe 42 should have a check valve 60 provided within it so that no water may enter thereinto from said reservoir 38.

From the hereinabove description it will be apparent that water 29 within troughs 15 is converted into steam by being spilled upon the roof of bulge 18 and from perforations in pipe 36. This process will be operative only when water is fed into troughs 15 from reservoir 38 under boiler and pump pressure, as otherwise it could not rise through pipes 32 to spill upon bulge 18 from pipe 36. After fire in fire box 10 has been made, it will require some time before the boiler will be heated sufficiently to convert water therein into steam and to generate pressure in reservoir 38 by supplying steam thereinto through pipe 43. In the interim no water would continually spill upon bulge 18, unless an auxiliary water supplying means upon bulge 18 is provided. That

means includes pipe 44 which is connected by one of its ends with the bottom of reservoir 38. The opposite end thereof connects with a rubber ball 45 and has a one-way valve 46 intermediately of its two ends. Said ball 45 is in turn connected with a vertical pipe 47 which is connected through the vertical wall of the boiler with one end of perforated pipe 36.

A small-powered electric motor 48 rotates cam 49 by means of belt 50. Off-centrally pivoted to said cam 49 is arm 51, which by the opposite end is connected with a lever 52 fulcrumed at 53 upon support 54. The opposite end of said lever 52 connects with arm 55. By means of said arm 51 oscillating movement to lever 52 will be imparted for intermittently actuating arm 55 in a substantially vertical direction for the purpose of intermittently pressing upon ball 45 for the purpose of ejecting water therefrom supplied from pipe 44 into pipe 47 and from the latter into pipe 36 so that the same may spill through perforations in the latter pipe. When sufficient amount of steam in boiler 14, and the consequent sufficient degree of pressure in reservoir 38 has been generated, pump P is actuated to assure a constant supply of water to bulge 18 through pipe 36 and from troughs 15, the supply of water into ball 45 and pipe 47 may thereupon be disconnected by closing valve 46 and stopping the operation of motor 48.

The entire boiler 14, closure 20, sealing connection therebetween, as well as fire box 10 may all be enclosed within an impervious and heat retaining cover 56. Gauge 57 for indicating the degree of steam pressure within boiler 14 and safety valve 58 for permitting escape of steam over a certain degree of pressure within boiler, are connected to roof 21 of closure 20, and of course should extend through cover 56.

40 For the sake of clearness fire box 10 as well as cover 56 have been eliminated from Fig. 2.

One end of pipe 36 may be capped as at 57'.

Flue 59 connecting with one of the end walls 30 of fire box 10, and below the perimeter of bulge 18, permits the escape of smoke and combustion gases into the chimney.

Optionally wings 37 may be provided with minute perforations 60, permitting draining of water therethrough and upon lateral faces of bulge 18, and below said wings 37. Any excess of water will spill over the upper edges of said wings 37.

Independently of the boiling of water in troughs 15 and below sealing plates 31, the water will rise through pipe 32 into the perforated pipe 36 by virtue of the supply of water under pressure through pipes 28 into said troughs 15 from said reservoir 38.

From the hereinabove description it will be apparent that walls of troughs 15 in conjunction with sealing plates 31 define hermetically sealed compartments into which a constant supply of water is fed under pressure, and in which water is preheated before the same is forced to rise through pipes 32 into perforated pipe 36.

Since water below sealing plates 31 will not normally rise through pipes 32 in perforated pipes 36 until an amount of steam has been generated in the boiler so as to create pressure within reservoir 38 through pipe 43, and pump is made operative, the auxiliary water feeding means into perforated pipe 36, including motor 48, ball 45 and pipe 44, is resorted to. This auxiliary means of course is rendered inoperative by disconnecting the operation of motor 48, as soon

as sufficient steam has been passed into reservoir 38 from boiler 14 through pipe 43.

Valve 46 is alternately opened and closed during the operation of the auxiliary water pumping means into pipe 47 for forcing water into perforated pipe 36. When said auxiliary water pumping means has performed its function motor 48 is then stopped and valve 46 is held in its closed position.

Check valve 61 is provided in pipe 47 so that water pumped into pipe 47 may not return back into ball 45 and pipe 44, but may flow into perforated pipe 36.

While there is described herein a preferred embodiment of the present invention, it is nevertheless to be understood that minor changes may be made therein without departing from the spirit and scope of the invention as claimed.

What I claim as new is:

1. A boiler comprising a pair of troughs, the inner lateral walls of said troughs being connected for defining a bulge, sealing plates in said troughs, said sealing plates in conjunction with the walls of said troughs defining hermetically sealed compartments, means for constantly supplying under pressure an amount of water into said compartments, pipes connecting with said compartments through said sealing plates, a perforated pipe disposed above said bulge and in a longitudinal relation therewith, said first named pipes connecting with said perforated pipe, and a fire box disposed below said troughs and said bulge, said fire box being adapted to receive fuel for burning therewithin, water receivable within said compartments being adapted to be preheated before the same spills upon said bulge through said perforated pipe, water spilling upon said bulge being adapted to be converted into steam.

2. A boiler comprising a pair of troughs, the inner lateral walls of said troughs being continuous for defining a bulge, sealing plates in said troughs, said sealing plates in conjunction with the walls of said troughs defining hermetically sealed compartments, means for constantly supplying under pressure an amount of water into said compartments, a fire box disposed below said troughs and said bulge, said fire box being

adapted to receive fuel for burning therewithin, water receivable within said compartments being adapted to be preheated, and means associated with said compartments for ejecting the preheated water therefrom and spilling the same upon said bulge, water spilling upon said bulge being adapted to be converted into steam.

3. A boiler comprising a pair of troughs, the inner lateral walls of said troughs being continuous for defining a bulge, sealing plates in said troughs, said sealing plates in conjunction with the walls of said troughs defining hermetically sealed compartments, said bulge extending above the plane of said sealing plates, means for constantly supplying under pressure an amount of water into said compartments, a fire box disposed below said troughs and said bulge, said fire box being adapted to receive fuel for burning therewithin, water receivable within said compartments being adapted to be preheated, and means associated with said compartments for ejecting the preheated water therefrom and spilling the same upon said bulge, water spilling upon said bulge being adapted to be converted into steam.

JOHN BILAN.
